ELECTROMAGNETIC VALVE
CONSTRUCTION

Robert B. Clay and George A. Goepfrich, Norwalk, Conn., assignors to The Skinner Chuck Company, Norwalk, Conn., a corporation of Connecticut

Application March 6, 1951, Serial No. 214,162

14 Claims. (Cl. 137—729)

1

It is the general object of the present invention to provide a valve of simplified low-cost construction which lends itself particularly to rapid, inexpensive and easy assembly during the manufacturing operation, or to similar disassembly as for repair purposes. Further, the construction is such as to permit quick and easy modification for operation in different ways such as a normally opened or a normally closed valve.

The full nature of the invention, together with all of its objects and advantages, will best be understood by reference to the following description of one illustrative embodiment thereof which is shown graphically in the annexed drawing in which:

The Fig. 1 is a cross sectional view axially through a valve of generally cylindrical configuration;

Fig. 2 is a top plan view of the valve illustrated in Fig. 1, and may also be considered as a bottom plan view since the top and bottom views are essentially the same;

Fig. 3 is a partial side plan view illustrating the key and key hole structures hereinafter more fully described;

Fig. 4 is a cross section along the line 4—4 of Fig. 1 illustrating better the cross section of the operating plunger of the valve;

While the Fig. 5 is a view similar to Fig. 1 of a modification.

Referring to the drawing, the principal operating elements of the valve thereshown may be considered as supported from and within a cylindrical outer containing casing 10 having a tubular conduit 11 affixed to the side walls thereof for the purpose of housing lead-in wires 12 which may extend through a suitable opening 13 in casing 10 for connection with the operating electromagnetic coil 14. Closing the open ends of the casing 10 are first and second annular end planes 15 and 16 respectively. These end plates preferably have outer diameters approximately equal to the inner diameter of casing 10, whereby they fit loosely within the casing except when fixed in position by the key and key hole means to be described below. The inner diameter of the end plates is approximately equal to the inner diameter of a cylindrical sleeve 17 of non-magnetic material (e. g. brass or nonmagnetic stainless steel) which, as shown, extends between the two end plates and which abuts loosely against them except when its position is fixed by the further elements to be described.

Affixed, as by brazing, to the end plates are first and second cylindrical port members 18 and

2

19 respectively. It will be noted that the member 19 rests against the end plate 16 by means of an annular shoulder 20 which serves as a positioning means between the end plate 16 and the member 19. The end plate and the member 19 may be affixed together as a unit prior to the overall assembly of the valve, as by brazing at their juncture in the vicinity of the shoulder 20. As shown, the lower portion 21 of member 19 extending through and below the end plate 16 has a diameter somewhat less than the upper portion 22 which extends outside of the end plate 16. Portion 21 has a diameter approximately equal to the inner diameter of sleeve 17 so as to engage the same in a snug fitting. The fitting is sealed by a sealing ring 22A of rubber or like material positioned in an annular groove 23 in the peripheral surface of portion 21. The central channel 24 extending axially through the member 19 will constitute a port for the valve; in this particular embodiment it may be considered as serving as an inlet port. The lower surface of the portion 21 is provided with an electrically conducting shading ring 25 serving the usual purpose of facilitating the alternating current operation of the coil 14.

As the drawing will indicate, the member 18 is fashioned substantially in the same manner as the member 19. It is brazed or otherwise affixed to the end plate 15 as a unit in the vicinity of the annular shoulder 26 constituting the dividing line between portions of different diameter on opposite sides of the end plate 15. Sealing ring 27 serves the same purpose as the sealing ring 22A, i. e., both seal fluid within the sleeve 17 and also facilitate assembly as will be indicated below. Member 18 differs from the member 19 to the extent that its inner end is provided with a frusto-conical section 28, the inner end of which constitutes a valve seat for the termination of the port 29 (considered as an outlet port in this modification) extending axially through the member 18.

The end plates 15 and 16 are firmly but removably positioned and affixed to the casing 10 by the following means. It will be noted (see Figs. 2 and 3) that the end plate 16 is provided on its periphery with a plurality of radially extending studs 30 which may be termed key studs; and further, that the upper edge of the casing 10 is provided with the same plurality of cross shaped key holes 31 (see Fig. 3). Key holes 31 comprise an axial key slot 32 extending axially along the casing 10, completely through the casing from inner to outer wall, and opening in the upper

edge 33 thereof; as well as a peripheral key slot 34 similarly extending from inner to outer wall of casing 10 and through the axial key slot 32. It will be apparent that the radial and axial key slots define a cross shaped opening or key hole extending from the edge of the casing 10 and opening in that edge. As Fig. 3 indicates, the key studs 39 rest in the bottom walls of the axial key slots 32. They are held firmly in that position by the resilient key pin 35 which, as Fig. 2 indicates, may comprise a generally U-shaped resilient member which is under compression such that it tends to expand the opening of the U. It will be seen that it is shaped to provide rounded key sections 36 which will fit into the peripheral key slots 34 when the key pin 35 presses outwardly to assume the position shown in the full lines in Fig. 2. By drawing together the ends 37 forming the opening of the U, as suggested by the dotted lines, the sections 36 may be withdrawn from the peripheral key slots. It will be noted then that with the sections 36 in the position shown in the Figs. 2 and 3, they lock the end plate 16 in position by preventing any motion of the key studs 39 out of the axial key slots 32.

The bottom end of plate 15 is held in position against the casing 10 by substantially the same means. A plurality of key holes 38, identical with the key holes 34, are provided along the lower edge of the casing 10, and plate 15 is provided with the same plurality of key studs 39 identical with key studs 33, and the end plate 15 is locked in position by a key pin 40 identical with the key pin 35.

For firmly positioning the coil 15 within the space between the sleeve 17 and the casing 10, there is provided a means for pressing it firmly against the end plate 16. This means comprises a floater plate 41 which has an annular shape substantially the same as that of the end plates 15 and 16 but somewhat more loosely fitting between the sleeve 17 and the casing 10 so that it may slide axially of the structure. A compression spring 42 is positioned between the floater plate 41 and the plate 15 such that by exerting pressure on the end plate 15 and the floater plate 41 it pushes the coil into firm engagement with the end plate 16.

A variety of fluid controlling elements to constitute a suitable valve mechanism may be included within the sleeve 17 for cooperation with the ports 24 and 29. In the Fig. 1 embodiment elements are provided to constitute a normally closed valve which employs the valve seat 28 as a normally closed element. An electromagnetic plunger 43 is mounted for sliding movement within the sleeve and is biased toward the seat 28 by a compression spring 44 engaging member 19 and the plunger 43 at its opposite ends. As the Fig. 4 indicates, plunger 43 is provided with a plurality of axially extending channels 45 on its outer surface as well as a central axial channel 46 communicating with the port 24 and with a plurality of radially extending channels 47 which open into the channels 45. Since the plunger 43 is to constitute a valve head for the valve seat 28, it is also provided with a resilient member 48 of rubber or like material set into a suitable recess in the lower end surface of the plunger 43.

The casing 10, and plates 15 and 16, floater plate 41, plunger 43, and members 18 and 19 may all be made of magnetic material. Sleeve 17 is preferably of nonmagnetic material such as brass or nonmagnetic stainless steel. The presence of

the member 48 in the lower end of the plunger 43 will serve to minimize the magnetic flux in the metallic portions below plate 41 and thus help to concentrate the flux in the path defined approximately by the end plate 16, floater plate 41, and the portions of the casing 10, member 19, and plunger 43 therebetween.

In operation, fluid will flow around the plunger 43 (i. e., through channels 45) as well as through the channels therein and thus facilitate movement of the plunger in the sleeve 17 by minimizing friction. The fluid flow will also help to close the valve when the coil is de-energized and thus tend to overcome any residual magnetic force that may be present. This flow also tends to cool the valve which is particularly important when eddy current due to alternating current operation tends to increase the heat losses.

In the modification illustrated in the Fig. 5, fluid controlling elements constituting a normally opened valve within the sleeve 17 are illustrated. Otherwise, the structure is the same as that of the preceding figures for which reason like numerals have been applied.

In Fig. 5, electromagnetic plunger 49 is mounted for sliding movement within the sleeve 17 and is biased away from a valve seat 50 through which fluid passes in flowing between the ports 24 and 29. Plunger 49 is provided with a resilient valve head member 51 for cooperation with the valve seat. A spring 52 normally biases the plunger 49 and the valve head 51 away from the valve seat 50 by virtue of the fact that the spring is under compression and engages the member 18 at one end and the bolt 53 at its other, the bolt 53 being affixed to the plunger 49. It will be apparent of course that when the coil 14 is energized, it will draw the plunger 49 toward the valve seat to bring the valve head 51 into closing engagement therewith, and that when the coil is de-energized, the spring 52 will draw the plunger back to the open position shown. The plunger, like the plunger in Fig. 1, is provided with a plurality of axially extending channels 54 on its surface (like the channels 45) and on its bottom radially extending channels 55 (like channels 47 in Fig. 1). Fluid may flow through these channels and also through channel 56 in member 18.

The merit of the foregoing construction for purposes of rapid and easy manufacture and assembly, or disassembly, will be readily apparent. Many of the parts, because of simplicity, may be fabricated by simple stamping or like operations.

For assembly, the lower unit comprising the member 18 and the lower end plate 15 may be inserted within the lower end of the casing 10 with key studs 39 in the bottom of their axial key slots; the sleeve 17 together with the spring 42, plate 41, coil 14, and the plunger and other valve parts, such as plunger 43, and spring 44, may then be inserted through the top opening of casing 10 preferably in the order of mentioning. The insertion of the sleeve 17 over the upper reduced diameter portion of member 18 is facilitated by the fact that the member 27 will compress within its groove in member 18 to ease the sliding action of the sleeve 17 over the member 18. Thereafter the upper unit comprising the member 19 and end plate 16 affixed together as a unit may be inserted in the upper end of casing 10 with the key studs 30 resting on the inward end face of axial key slots 32 and member 19 in sleeve 17. At this stage, the pressure of the compression spring 42 tends to push the end plates 15

and 16 outwardly. However, while the end plates 15 and 16 are held with their key studs 30 and 39 in engagement with the inward end of the axial key slots, the key pins 35 and 40 are inserted to lock the key studs in the position shown in Fig. 1. It is understood that the engagement of the sections 36 of the key pins with the outer walls of the peripheral key slots 34 prevents motion of the end plates 15 and 16 or their key studs out of the key holes. Key pins 35 and 40 are inserted by drawing their ends 37 together sufficiently to permit the insertion of the key pins within the casing 10, and then they are released to permit resilient engagement in the peripheral key slots. Disassembly may be accomplished simply by removing the key pins in a converse manner and removing the various parts in an order reverse to that indicated for assembly.

What is claimed is:

1. A valve structure comprising a sleeve, a casing surrounding said sleeve and having key holes in the ends thereof, end plates closing the ends of the space between said sleeve and casing and having peripheral key studs engaging said key holes, a key pin holding the key studs in said key holes, an electromagnetic coil surrounding said sleeve between said sleeve and casing, and valve means in said sleeve for operation by said coil.

2. A structure as in claim 1 in which each said key hole comprises an axial slot to receive a key stud and a peripheral key slot through said axial slot, the key pin comprising a resilient spring resiliently engaging in the peripheral key slots to hold the key studs in the key holes.

3. A valve structure comprising a sleeve, a casing surrounding said sleeve and having key holes in the ends thereof, end plates closing the ends of the space between said sleeve and casing and having peripheral key studs removably engaging said key holes, a key pin holding the key studs in said key holes, port members extending through said end plates and removably engaging with said sleeve whereby said sleeve constitutes a fluid conduit between said port members, an electromagnetic coil surrounding said sleeve between said sleeve and casing, and valve means in said sleeve for cooperation with one of said port members and operation by said coil.

4. A structure as in claim 3 in which each said key hole comprises an axial slot to receive a key stud and a peripheral key slot through said axial slot, the key pin comprising a resilient spring resiliently engaging in the peripheral key slots to hold the key studs in the key holes.

5. A valve structure comprising a sleeve, a casing surrounding said sleeve and having key holes in the ends thereof, end plates closing the ends of the space between said sleeve and casing and having peripheral key studs engaging said key holes, an electromagnetic coil surrounding said sleeve between said sleeve and casing, resilient means between said coil and one of said end plates pressing against said one end plate and coil and acting through said coil against the other of said end plates, means locking said key studs in said key holes whereby said end plates are firmly held in position, and valve means in said sleeve for operation by said coil.

6. A structure as in claim 5 in which each said key hole comprises an axial slot to receive a key stud and a peripheral key slot through said axial slot, said locking means comprising a resilient key pin resiliently engaging in the peripheral key slots to hold the key studs in the key holes.

7. A valve structure comprising a sleeve, a casing surrounding said sleeve and having key holes in the ends thereof, end plates closing the ends of the space between said sleeve and casing and having peripheral key studs removably engaging said key holes, port members extending through said end plates and removably engaging with said sleeve whereby said sleeve constitutes a fluid conduit between said port members, an electromagnetic coil surrounding said sleeve between said sleeve and casing, resilient means between said coil and one of said end plates pressing against said one end plate and coil and acting through said coil against the other of said end plates, resilient removable means locking said key studs in said key holes whereby said end plates are firmly but removably held in position, and valve means in said sleeve for cooperation with one of said port members and operation by said coil.

8. A structure as in claim 7 in which each said key hole comprises an axial slot to receive a key stud and a peripheral key slot through said axial slot, said locking means comprising a resilient key pin resiliently engaging in the peripheral key slots to hold the key studs in the key holes.

9. A valve structure comprising a sleeve, a casing surrounding said sleeve and having key holes in the ends thereof, end plates closing the ends of the space between said sleeve and casing and having peripheral key studs engaging said key holes, an electromagnetic coil surrounding said sleeve between said sleeve and casing, a floater plate surrounding said sleeve between said sleeve and casing, a compression spring between said floater plate and one of said end plates pressing against said one end plate and floater plate and acting through said floater plate and coil against the other of said end plates, means locking said key studs in said key holes whereby said end plates are firmly held in position, and valve means in said sleeve for operation by said coil.

10. A structure as in claim 9 in which each said key hole comprises an axial slot to receive a key stud and a peripheral key slot through said axial slot, and said locking means comprises a resilient key pin engaging in the peripheral key slots to hold the key studs in the key holes.

11. A valve structure comprising a sleeve, a casing surrounding said sleeve and having key holes in the ends thereof, end plates closing the ends of the space between said sleeve and casing and having peripheral key studs removably engaging said key holes, port members extending through said end plates and removably engaging with said sleeve whereby said sleeve constitutes a fluid conduit between said port members, an electromagnetic coil surrounding said sleeve between said sleeve and casing, a floater plate surrounding said sleeve between said sleeve and casing, a compression spring between said floater plate and one of said end plates pressing against said one end plate and floater plate and acting through said floater plate and coil against the other of said end plates, resilient removable means locking said key studs in said key holes whereby said end plates are firmly but removably held in position, and valve means in said sleeve for cooperation with one of said port members and operation by said coil.

12. A structure as in claim 11 in which each said key hole comprises an axial slot to receive a key stud and a peripheral key slot through said axial slot, and said locking means comprises a resilient key pin engaging in the peripheral key slots to hold the key studs in the key holes.

13. A structure as in claim 11 in which said valve means comprises a channelled plunger for said coil having a valve head thereon and being slideably mounted within said sleeve for motion between said port members, and spring means between said plunger and one of said port members for biasing said plunger toward the other of said port members, said other port member having a valve seat thereon for cooperation with said valve head the valve head being on that end of the plunger facing the valve seat.

14. A structure as in claim 11 in which said valve means comprises a channelled plunger for said coil having a valve head thereon and being slideably mounted within said sleeve for motion between said port members, and spring means between said plunger and one of said port mem-

5

bers for biasing said plunger away from the other of said port members, said other port member having a valve seat thereon for cooperation with said valve head the valve head being on that end of the plunger facing the valve seat.
